[57] CLAIM

The ornamental design for combined kettle and ash can for barbecue grill, substantially as shown and described.

DESCRIPTION

FIG. 1 is a perspective view of a combined kettle and ash can for barbecue grill, showing my new design, the legs, wheels and support brace are shown in broken lines for illustrative purposes only and form no part of the claimed design;

FIG. 2 is a side elevational view thereof;

FIG. 3 is a rear elevational view thereof;

FIG. 4 is top plan view thereof;

FIG. 5 is bottom plan view thereof;

FIG. 6 is a front elevational view thereof; and

FIG. 7 is an exploded front elevational view thereof with the legs shown fragmented for ease of illustration.
